UNITED STATES PATENT OFFICE.

MORITZ RHEINAUER, OF NEW YORK, N. Y.

MACHINE FOR MARBLING PAPER.

1,405,163.

Specification of Letters Patent.

Patented Jan. 31, 1922.

Application filed July 23, 1920. Serial No. 398,486.

To all whom it may concern:

Be it known that I, MORITZ RHEINAUER, a citizen of the United States of America, residing at New York city, county and State 5 of New York, have invented certain new and useful Improvements in Machines for Marbling Paper, of which the following is a full, clear, and exact description.

This invention relates to improvements in 10 paper marbling machines, one of the objects being to provide a device that will more evenly produce a marble effect upon paper than is possible by the machines and methods now employed. One of the difficulties 15 encountered in marbling paper is to cause the color to be applied to the paper along the longitudinal edges thereof as evenly as it is applied to said paper intermediate the longitudinal edges. To marble 20 paper a trough is employed which contains a sizing upon the surface of which color is sprayed. The paper to be marbled is drawn through the sizing to cause the color to adhere to the paper, the trough containing 25 the sizing is but little wider than the paper. So far as I am aware, as now commonly practised the paper is drawn through the sizing, said sizing being normally dormant, that is to say, not normally in motion. As 30 the paper is drawn through the sizing, it picks up the color, but the color along the vertical sides of the trough will lay in pools, or, in other words, remain stagnant, while the color intermediate the sides of the trough 35 will be caused to move along with the paper, thereby giving it time to adhere to the paper, but the color at the sides of the trough does not have time to thoroughly adhere to the paper, and hence the coloring 40 along the edges of the paper will be light or irregular, because the color will stick to the sides of the trough and will not be drawn along with the paper.

To overcome the above mentioned objectionable features, I provide a machine arranged to cause the sizing with the color to move, preferably at about the same speed as the paper, not only intermediate the sides of the trough but at the sides to prevent the 45 stagnation of the color at the sides of the trough.

The apparatus to carry out my invention will now be described, in conjunction with the accompanying drawings, forming part 50 of this specification wherein:

Fig. 1 illustrates a sectional plan view of

my improved form of trough, the color applying devices and paper to be marbled being omitted;

Fig. 2 is an enlarged fragmentary sectional view the section being taken on a line 2-2 in Fig. 1;

Fig. 3 is an enlarged end view, looking from the right in Fig. 1;

Fig. 4 is an enlarged sectional view, illustrating one of the color applying devices and cleaning drums;

Figs. 5 and 6 are fragmentary detail views of one of the belts and one of the trays, illustrating means to connect same;

Fig. 7 is an enlarged sectional detail view, illustrating the means to cause paper to come into contact with the sizing;

Fig. 8 is a diagrammatic side elevation of the entire machine, broken away;

Fig. 9 is a detail fragmentary plan view, illustrating one of the color applying devices.

As herein embodied, my invention consists of a channeled frame member 10, in this instance in rectangular form, but having rounded ends as indicated by 11 and 12, the radial point of the rounded ends being coincident with the axis of the shaft of idler pulleys 13 and 14, said shafts being indicated 80 by 15. The pulleys 13 and 14 support a belt 16, preferably metallic (brass for instance), which operates close to or in contact with the adjacent vertical sides 17 of the channeled frame 10. Adjacent to or in 85 contact with each outer vertical side 18 of the frame 10, I locate a belt 19 which passes around pulleys 20 and 21 and over idlers 22. As can be seen, the belt 19 is double along the sides 18, the outer run of the belt 90 operating in the same direction as the inner belt 16. The pulleys 21 and 14 are driven pulleys, being operated by a driven shaft 23 (Fig. 3), and intermeshing gears. The shaft 95 15 for the pulley 14 carries a gear 24 meshing with a gear 25 on the shaft 23. Each shaft 26 for the pulleys 21 carries a gear 27 meshing with the gear 28 on shaft 23. The above mentioned gears will be proportioned to cause belts 16 and 19 to travel at the same 100 speed.

The shaft 23 carries a sprocket 29 which operates a chain 30 which in turn, by means of a sprocket pulley 31, actuates a cleaning device consisting of, in this instance, two 110 heated drums 32 and 33. The cleaning device or drums 32 and 33 are heated and main-

tained dry by steam or hot air introduced thereinto through a duct 34 and hollow shaft 36; a duct 37 serving as an exhaust passage for the heating element. The drums 32 and 33 are positioned to cause them to dip slightly into the sizing, indicated by 38. As the sizing 38 and its color, sprayed thereupon by the spraying devices 39, will be in motion or caused to move along 10 or through the trough with the belts 16 and 19, the drums 32 and 33, which will be warm and dry, will pick up the color left upon the surface of the sizing after it has passed the paper, which will be located, as indicated 15 by dotted lines 40 in Fig. 1. In other words, the drums will clean the surface of the sizing or take off the greater part of the color which was left after having passed the marbling station or paper, leaving a comparatively clean surface for the newly applied 20 color. In connection with the drum I preferably employ scrapers 41 which will cut the color, indicated by 42, Fig. 4, off the surface of the drums. Each color sprayer 39 consists of a pan 43 containing color 44 and a drum 45 upon the surface of which the color adheres. The color is wiped off the surface of drum 45 by means of wire brushes 46 carried by a drum 47. The drums 45 25 and 47 are connected together by gears 48, 49 and 50. The shaft 51 of drum 45 carries sprocket wheels 52 and 53, the sprocket 53 of the first sprayer A being connected to a sprocket pulley 54 by a chain 55, the pulley 54 being carried by shaft 23 (see Fig. 35 8). The sprayer at B will be operated by a chain 56 actuated by sprocket pulley 52 on sprayer at A, and the sprayer at C will be operated by a chain 57 from a sprocket 40 pulley on sprayer B similar to sprocket pulley 52 on sprayer A. The paper to be marbled will be carried in the form of a reel 58, for instance, and run over an idler 59; thence under and partly around a drum 45 60; thence over an idler 61 to a drying device (not shown). The reel 58, idlers 59 and 61, will be supported by brackets 62 carried by the frame 10. As can be seen in Fig. 7, the paper web, indicated by 63, is caused to 50 dip into the sizing slightly below the surface thereof, or just enough to cause the color which floats upon the sizing to contact with the surface of the web.

During the operation of the device, the 55 sizing will be constantly in motion, or in other words, will travel through the channel 64. To cause the sizing to travel through the trough, I provide trays 65 which are removably connected to the belt 16. To connect the belt 16 and the trays, I provide the said belt with pins 66, which project therefrom (see Fig. 5), to engage ears 67 struck up from the trays. One end of each tray 60 is turned up to form a flange 68. The trays 65 are arranged in the trough to cause the

flanges 68 to come together; hence a plurality of paddles will be formed. The paddles will cause the sizing to circulate or move around through the channel. As has been stated, the metallic belts 16 and 19 move or travel; therefore, the trays 65 will travel through the channel, causing the sizing to also travel and causing the floating colors to come in contact with the web 63, which operates in a fixed plane. While the belts 19 75 70 do not contribute to the movement of the trays, they act to prevent stagnation of the sizing along the adjacent sides of the channel. The belt 16 also prevents stagnation, on the part of the sizing, along the adjacent sides 17 of the channel. To prevent formation of waves due to the movement of the trays and sizing, I provide dam-members 69 and 70 disposed, as indicated in Fig. 1. The dam-members will prevent the sizing 80 85 from being rippled or waved at that portion where the color is applied whereby a comparatively even surface will be maintained on the part of the sizing.

One of the features of the invention is 90 the fact that the sizing is caused to travel through the trough, the paper being operated in a fixed plane, whereby the color is carried to the paper which is caused to travel at the about the same speed. The moving 95 belts 16 and 19 will prevent the sizing, and color thereupon, from stagnating at the sides of the trough. The color will be sprayed upon the surface of the sizing by the spraying device at A, B and C. As this spraying 100 feature is old in the art of marbling paper, it will not be described in detail. I prefer to provide a feeding device for the web of paper, indicated by 72 in Fig. 7, said device consisting of a feed roller 73, bearing upon 105 the idler 61. The roller 73 may be driven by a pulley 74 and belt 75.

The purpose of the dam-members 69 and 70 is to prevent rippling or waving at the point where color is applied to the sizing, or, in other words, between dam-member 69 and paper web 63. The tendency of the flanges 68 would be to ripple the sizing at the rounded end 12 of the frame during their course in a circular path. The members 69 and 70 will prevent the waves or ripples from extending to the portion of the frame where color is applied to the sizing. The ripples or waves cannot pass the dam-member 69, and dam-member 70 aids in arresting the onward course of the ripples. The cleaning roller 32 will take up any color that may pass the dam-members.

Having described my invention what I claim is:

1. In a paper marbling machine, a container for sizing, a movable bottom member within the container, and movable side members independent of the bottom member also within the container, all arranged to im- 130 125

part movement to the sizing within the container.

2. In a paper marbling machine, a container for sizing, means to actuate the paper to be marbled in a fixed plane, means to apply coloring material to the surface of the sizing, movable means within the container to cause the sizing and color material carried thereby to contact with the paper, and means to clean that portion of the surface of the sizing which has passed the paper.

3. In a paper marbling machine, a container for sizing, means to actuate the paper to be marbled in a fixed plane, means to apply coloring material to the surface of the sizing, movable means within the container to cause the sizing and color material carried thereby to contact with the paper, and means to prevent the surface of the sizing from rippling at that portion thereof where the color is applied.

4. In a paper marbling machine, a container for sizing, means to actuate the paper to be marbled in a fixed plane, means to apply coloring material to the surface of the sizing, movable means within the container to cause the sizing and color material carried thereby to contact with the paper, rotatable drums to clean that portion of the surface of the sizing which has passed the paper, and means to heat said drums.

5. In a paper marbling machine, a container for sizing, movable belts at each side of the container, means carried by one of said belts to impart movement to the sizing, and means to actuate the belts.

6. In a paper marbling machine, a container for sizing, movable belts at each side of the container, trays carried by one of said belts, and flanges carried by the trays acting as paddles to impart movement to the sizing.

7. In a paper marbling machine, a frame consisting of channelled members arranged in parallelism and connected at each end by a rounded channel, movable belts operable along the sides of the parallel channelled portions of the frame, means to operate the

belts, and means to feed a web of paper, to be marbled, in a fixed plane at one end of the frame.

8. In a paper marbling machine, a rectangular channelled container rounded at each end to contain sizing, a belt at each side of the container, a belt intermediate the side belts, means located between the adjacent runs of said belts to impart motion to the sizing, means to feed a web of paper, to be marbled, in a fixed plane between adjacent runs of said belts at one end of the container, means to operate the belts.

9. In a paper marbling machine, a rectangular channelled container rounded at each end to contain sizing, a belt at each side of the container, a belt intermediate the side belts, means located between the adjacent runs of said belts to impart motion to the sizing, means to feed a web of paper, to be marbled, in a fixed plane between adjacent runs of said belts at one end of the container, means to operate the belts, and means also located between adjacent runs of said belts to prevent rippling of the sizing at the point thereof where color is applied.

10. In a paper marbling machine, a rectangular channelled container rounded at each end to contain sizing, a belt at each side of the container, a belt intermediate the side belts, means located between the adjacent runs of said belts to impart motion to the sizing, means to feed a web of paper, to be marbled, in a fixed plane between adjacent runs of said belts at one end of the container, means to operate the belts, means also located between adjacent runs of said belts to prevent rippling of the sizing at the point thereof where color is applied, and means to clean that portion of the surface of the sizing that has passed the paper.

Signed at New York city, N. Y., this 21 day of July, 1920.

MORITZ RHEINAUER.
